UNITED STATES PATENT OFFICE.

HARRY G. DAVIS, OF WILLIAMSPORT, PENNSYLVANIA, ASSIGNOR TO ELECTRIC PRESS BULLETIN COMPANY, OF WILLIAMSPORT, PENNSYLVANIA, A CORPORATION OF DELAWARE

TELEGRAPH-TRANSMITTER APPARATUS.

978,435.

Specification of Letters Patent. Patented Dec. 13, 1910.

Application filed October 18, 1909. Serial No. 523,189.

To all whom it may concern:

Be it known that I, HARRY G. DAVIS, a citizen of the United States, and resident of Williamsport, Lycoming county, State of Pennsylvania, have made certain new and useful Inventions Relating to Telegraph-Transmitter Apparatus, of which the following is a specification, taken in connection with the accompanying drawings, forming part of the same.

This invention relates to telegraph transmitter apparatus and relates especially to transmitting apparatus for actuating telegraph printers of the type described in the application of Campbell and Davis, 462,059, filed November 11, 1908.

In the accompanying drawings showing in a somewhat diagrammatic manner an illustrative embodiment of this invention, Figure 1 is a transverse sectional view of the transmitter; Fig. 2 is a longitudinal section thereof; Fig. 3 is a detailed plan view showing the unison arm mounting.

In the illustrative embodiment of this invention shown in the drawings the transmitter may comprise the pin drum 1 rigidly mounted on the drive shaft 54 which may be rotated through the frictional drive clutch 47 or other devices giving a slight torque and allowing slip when the drum is held against rotation. A spirally arranged series of pins 2 are mounted on the drum so as to coöperate with a corresponding series of latches 3 mounted on the latch pin 20 at the upper end of the latch arms 9 carried at either end of the latch shaft 10 as indicated in Fig. 1. The series of keys 4, 5 may be arranged as in a regular typewriter keyboard and pivoted about the key pin 7 in the frame member 8. The latches may be connected with the keys in any desired way as by the stirrups 6 loosely connecting each latch with its corresponding key which of course is normally held in raised inoperative position by suitable light springs, such as 24. The latch arm 9 operates between the two stops 12, 13 and is normally held out against the stop 12 by the actuating contact spring 16 which is in engagement with the latch lug 19. This spring is electrically connected with the wire 17 and is adapted to engage the contact 14 connected to the wire 18 when the lug is pressed backward by any latch being brought into engagement with the pin on

the drum which tends to rotate as indicated by the arrow.

The usual unison thread 43 may be mounted on the drive shaft 54 as indicated in Fig. 2 and be engaged by a suitable pin on the unison arm 28 which also carries the unison stud 26 for engagement with a corresponding stud on the unison crank 56 mounted on the drive shaft. As indicated in Fig. 1 this unison arm 28 is pivotally secured to the stud 29 and is provided with an inclined cam surface with which the coöperating releasing cam 35 on the printing lever 31 is adapted to engage so as to raise this unison arm out of coöperation with the unison thread and allow it to swing back into its initial position at the right of this thread in Fig. 2 as is usual so that every time one of the latches comes into engagement and throws the latch arm 9 backward the link 11 through its pivot 30 correspondingly swings the printing lever 31 mounted on its pin 40 so as to disengage and reset the unison arm.

The drive shaft 54 may be provided with a suitable type wheel 39 splined thereto by the feather 27 and controlled in its longitudinal movement by a suitable escapement bar 33 mounted by the brackets 41 on the rod 34 and engaging the collar 61 on the type wheel, so that the spring 42 shown in dotted lines in Fig. 2 normally tends to draw this escapement bar and type wheel to the right, its movement being limited by the usual typewriter escapement pawls 32 which feed the type wheel forward one space whenever the printing lever 31 is oscillated. This printing lever carries the printing bar 36 which is adapted to bring the paper sheet 37 into engagement with the characters on the type wheel 39 so as to print therefrom, the characters being of course inked by any suitable inking device not shown.

A suitable unison lever 23 may be mounted as indicated in Fig. 1 to coöperate with the end of the unison arm 28 when this arm has been moved to its extreme position in which the stud 26 engages the unison crank 56 indicated in Figs. 1 and 2, and locks after arm 28 has been moved a predetermined distance sufficient for instance to allow the drum shaft to make one more revolution. Under these conditions the unison lock or bar 21 supported on the arms 22 is rigidly held beneath the key levers so as to prevent any

of the regular character keys being depressed until this unison lock is released by the release of the unison arm from its extreme operative position. As is indicated in Fig. 2, however, the lock 21 does not project under the unison key 5 so that this key may under these conditions be readily depressed, throwing down the unison latch 38 so that its inclined or cam surface 103 engages the corresponding unison pin on the stationary drum, as is indicated in Fig. 1, thus wedging back the latch arms 9 and actuating the contacts and other devices described.

The interrupter or commutator segments 44, 45 may as indicated be mounted on the drive shaft 54 and electrically energized by the brushes 50, 51 engaging the sleeves 146, 46 respectively so as to positively or negatively energize the contacts 44, 45 from the batteries or other sources of electricity 48, 49. The corresponding brushes 144 and 145 are similarly energized by their engagement with the commutator segments 44, 45 to send out the alternating electrical impulses over the lines to the various controller and printing devices at the receiving stations. These alternating impulses normally pass through the transmitter resistance 52 so as to transmit moderate selective impulses to the various selector devices at the receiving station, but when the latch arms are forced back by engagement of any of the latches with the pin drum the contacts 14, 16 are brought into engagement and complete the shunt circuit through the connected wires 17, 18, so that a stronger actuating impulse may thus be transmitted to the receiving device. This stronger actuating impulse may as indicated in Fig. 2 operate a suitable signal device, such as the signal lamp 53 connected with each line leading to the corresponding receiving device which may comprise a releasing resistance or other means for reducing the current strength and correspondingly affecting the signal device at the sending station when the printing operation is completed in the machine connected with that particular line.

It is of course understood that any number of controller and printing devices at different stations may be connected to the same transmitter through similar actuating contacts 16 which are operated by the same latch lug or projection 19, these actuating contacts being similarly connected with corresponding signal lamps and transmitter resistances and with the same or similar interrupters on the drive shaft 54.

If desired a suitable cushioning device may be connected with the latch arms to minimize undesirable impact when the transmitter is rapidly operated. This cushioning device may as indicated in Fig. 1 comprise a suitable pneumatic cylinder 96 mounted on the frame and provided with the adjustable

throttling or control valve 98. The piston 95 in this cushioning cylinder has its rod 94 forced into engagement with the corresponding latch arm 9 by the spring 97 which may aid in returning the latch member to normal position, so that in this way the desired amount of pneumatic cushioning action may be secured as the latch member is thrown back by the pin drum.

Having described this invention in connection with an illustrative embodiment thereof, to the details of which disclosure the invention is not of course to be limited, what is claimed as new and what is desired to be secured by Letters Patent is set forth in the appended claims.

1. In telegraph transmitter apparatus, a frictionally operated drive shaft and connected pin drum, a series of pins on said drum, a latch shaft, latch arms connected to said latch shaft, a latch pin connected to said latch arms, a series of latches mounted on said latch pin and coöperating with the corresponding pins on said pin drum, a corresponding series of character keys operatively connected with said latches, a unison device operated by said drive shaft and comprising a unison arm, a unison lock in the path of said character keys, a connected unison lever in the path of said unison arm and held against movement when said unison device is in actuating position, a unison key, a connected unison latch having a cam surface coöperating with a unison pin on said drum, a pneumatic cushioning cylinder having an adjustable throttling valve coöperating with one of said latch arms, a spring pressed piston in said cylinder normally engaging said latch arms to cushion the same, a latch lug mounted on one of said latch arms, an electrical actuating contact in coöperating with said latch lug to be closed thereby when said latches are actuated, a type wheel connected with said drive shaft, printing devices coöperating with said type wheel actuated by one of said latch arms, means including an interrupter mounted on said drive shaft to generate alternating electrical impulses, a transmitter resistance through which said impulses normally pass to the line and a signal lamp and said actuating contact in shunt around said transmitter resistance.

2. In telegraph transmitter apparatus, a frictionally operated drive shaft and connected pin drum, a series of pins on said drum, a latch shaft, latch arms connected to said latch shaft, a latch pin connected to said latch arms, a series of latches mounted on said latch pin and coöperating with the corresponding pins on said drum, a corresponding series of character keys loosely connected with said latches, a unison device operated by said drive shaft and comprising

a unison arm, a unison lock in the path of said character keys, a connected unison lever in the path of said unison arm and held against movement when said unison device is in actuating position, a unison key, a connected unison latch having a cam surface coöperating with a unison pin on said drum, an electrical actuating contact 5 in cooperation with said latch lug to be closed thereby when said latches are actuated, a type wheel slidably mounted on said drive shaft, a printer bar and printing lever connected with and actuated by one of said 10 latch arms, a feed device for said type wheel controlled by said printing lever, means comprising an interrupter mounted on said drive shaft to generate alternating electrical impulses, a transmitter resistance through 15 which said impulses normally pass to the line and a signal and actuating circuit comprising a signal lamp and said actuating contact in shunt around said transmitter resistance.

20 3. In telegraph transmitter apparatus, a normally operated drive shaft and connected pin drum, a series of pins on said drum, a latch shaft, a latch arm connected to said latch shaft, a latch pin connected to said 25 latch arm, a series of latches mounted on said latch pin and coöperating with the corresponding pins on said drum, a corresponding series of character keys connected with said latches, a unison device connected to 30 said drive shaft and comprising a unison arm, a unison lock in the path of said character keys having a connected unison lever in the path of said unison arm and held against movement when said unison device 35 is in actuating position, a unison key, a connected unison latch having an actuating member coöperating with a unison pin on said drum, an electrical actuating contact coöperating with said latch arm to be closed 40 thereby when said latches are actuated, means comprising an interrupter connected with said drive shaft to generate electrical impulses, a transmitter resistance through 45 which said impulses normally pass to the line, a signal and actuating circuit comprising a signal lamp and said actuating contact in shunt around said transmitter resistance.

50 4. In telegraph transmitter apparatus, a normally operated drive shaft and connected pin drum, a series of pins on said drum, a movably mounted latch arm, a latch pin connected to said latch arm, a series of latches mounted on said latch pin and coöperating with the corresponding pins on 55 said drum, a corresponding series of character keys loosely connected with said latches, a unison device connected to said drive shaft comprising a unison arm, a unison lock in the path of said character keys and a connected unison lever in the path of said uni-

60 ton arm held against movement when said unison device is in actuating position, a unison key, a connected unison latch having a cam surface coöperating with a unison pin on said drum, an electrical actuating contact coöperating with said latch arm to be closed thereby when said latches are actuated, means comprising an interrupter connected to said drive shaft to generate electrical impulses, a transmitter resistance through 65 which said impulses normally pass to the line and a signal and actuating circuit comprising a signal device and said actuating contact connected in shunt around said transmitter resistance.

70 5. In telegraph transmitter apparatus, a pin drum, a series of pins on said drum, a latch device and latches connected to said latch device and coöperating with the corresponding pins on said drum, a corresponding series of keys connected with said latches, a pneumatic cushioning device connected with said latch device, an electrical actuating contact in coöperation with said latch device to be operated thereby when 75 said latches are actuated, means comprising an interrupter connected with said pin drum, to generate electrical impulses, a transmitter resistance through which said impulses pass to the line and a signal and actuating circuit comprising a signal device and said actuating contact connected in shunt around said transmitter resistance.

80 6. In telegraph transmitter apparatus, a pin drum provided with pins, a latch device, 85 latches connected to said latch device and coöperating with the corresponding pins on said drum, means to operate said latches, a cushioning device connected to said latch device, an electrical actuating contact coöperating with said latch device to be closed thereby when said latches are actuated and an interrupter connected with said pin drum and said actuating contact.

90 7. In telegraph transmitter apparatus, a pin drum, latches and a latch device coöperating with said pin drum, a pneumatic cushioning device connected with said latch device, an actuating contact coöperating with said latch device to be operated thereby when said latches are operated and means comprising an interrupter connected with 95 said pin drum and said actuating contact to generate electrical impulses.

100 8. In telegraph transmitter apparatus, a pin drum, a series of pins on said drum, a latch device, latches connected to said latch device and coöperating with the corresponding pins on said drum, a corresponding series of keys connected with said latches, an 105 electrical actuating contact in coöperation with said latch device to be closed thereby when said latches are actuated, means comprising an interrupter connected with said pin drum to generate electrical impulses, a 110

115 120 125 130

- transmitter resistance through which said impulses pass to the line and a signal and actuating circuit comprising a signal device and said actuating contact connected in shunt around said transmitter resistance.
9. In telegraph transmitter apparatus, a pin drum, a series of pins on said drum, a latch device, latches connected to said latch device, a series of keys connected with said latches, an electrical contact coöperating with said latch device to be closed thereby when said latches are actuated, means comprising an interrupter connected with said pin drum to generate electrical impulses, a transmitter resistance through which said impulses normally pass to the line and a signal and actuating circuit comprising a signal device and said actuating contact connected in shunt around said transmitter resistance.
10. In telegraph transmitter apparatus, a pin drum provided with pins, a series of keys and latches coöperating with said pin drum, an electrical actuating contact and means to close said contact when said latches are actuated, means comprising an interrupter connected with said pin drum to generate electrical impulses, a transmitter resistance through which said impulses normally pass to the line and a signal and actuating circuit comprising a signal device and said actuating contact connected in shunt around said transmitter resistance.
11. In telegraph transmitter apparatus, a pin drum provided with pins, a latch device, and a connected series of keys and latches coöperating with said pin drum, an electrical actuating contact coöperating with said latch device to be closed thereby when said latches are actuated, means comprising an interrupter connected with said pin drum to generate electrical impulses and a signal and actuating circuit comprising a signal device and said actuating contact to transmit stronger electrical impulses to the line when said actuating contact is operated.
12. In telegraph transmitter apparatus, a pin drum provided with pins, a latch device and a connected series of keys and latches coöperating with said pin drum, an electrical actuating contact coöperating with said latch device, a cushioning device coöperating with said latch device to cushion its action, means comprising an interrupter connected with said pin drum to generate electrical impulses and a signal and actuating circuit comprising a signal device and said actuating contact to transmit stronger electrical impulses to the line when said actuating contact is operated.
13. In telegraph transmitter apparatus, a pin drum provided with pins, a latch device and a connected series of keys and latches coöperating with said pin drum, an electrical actuating contact coöperating with 65 said latch device to be closed thereby when said latches are actuated, a pneumatic cushioning device coöperating with said latch device, means comprising an interrupter connected with said pin drum to generate 70 electrical impulses and a signal and actuating circuit comprising a signal device and said actuating contact to transmit stronger electrical impulses to the line when said actuating contact is operated. 75
14. In telegraph transmitter apparatus, a pin drum provided with pins, a latch device and a connected series of keys and latches coöperating with said pin drum, an electrical actuating contact coöperating with 80 said latch device to be closed thereby when said latches are actuated, a pneumatic cushioning cylinder having an adjustable throttling valve and coöperating with said latch device, means comprising an interrupter connected with said pin drum to generate 85 electrical impulses and a signal and actuating circuit comprising a signal device and said actuating contact to transmit stronger electrical impulses to the line when said actuating contact is operated. 90
15. In telegraph transmitter apparatus, a pin drum, a latch device coöperating with said pin drum, a pneumatic cushioning device connected with said latch device, said cushioning device comprising a cushioning cylinder and means to adjust the action of said cushioning cylinder, an actuating contact coöperating with the said latch device to be operated thereby when said latches are operated and means comprising an interrupter connected with said pin drum and said actuating contact to generate electrical impulses. 95
16. In telegraph transmitter apparatus, a pin drum, a latch device coöperating with said pin drum, a pneumatic cushioning device connected with said latch device, said cushioning device comprising a cushioning cylinder having an adjustable throttling valve to govern its action, an actuating contact coöperating with the said latch device to be operated thereby when said latches are operated and means comprising an interrupter connected with said pin drum and said actuating contact to generate electrical impulses. 100 110 115
